MEANS AND METHOD FOR TRANSMITTING
SYNCHRONIZING PULSES IN TELEVISION

Philo T. Farnsworth, San Francisco, Calif., assignor, by mesne assignments, to Farnsworth Television & Radio Corporation, Dover, Del., a corporation of Delaware

Application July 11, 1936, Serial No. 90,173

13 Claims. (Cl. 178—69.5)

My invention relates to television, and more particularly to a means and method of transmission of synchronizing pulses, both high and low frequencies.

5 Among the objects of my invention are: to provide a train of unidirectional synchronizing pulses; to provide a train of unidirectional synchronizing pulses having a lower frequency pulse modulated thereon; to provide a means and 10 method whereby such a train of unidirectional synchronizing pulses is regularly reduced in amplitude to provide a lower frequency pulse; to provide a means and method of separate transmission of synchronizing pulses and related television signals; and to provide a means and 15 method of modulating a series of relatively high frequency synchronizing pulses with a lower frequency synchronizing pulse.

Other objects of my invention will be apparent 20 or will be specifically pointed out in the description forming a part of this specification, but I do not limit myself to the embodiment of the invention herein described, as various forms may be adopted within the scope of the claims.

25 Referring to the drawings:

Figure 1 is a diagrammatic representation of a television transmitting station wherein low frequency synchronizing pulses are modulated onto high frequency synchronizing pulses, the combined pulses then being modulated together with the signal onto a carrier for simultaneous propagation.

Figure 2 is a similar diagrammatic representation of a transmitting station, wherein the low frequency pulses are modulated onto the high frequency pulses, these pulses being modulated onto a carrier for propagation. Television signals are modulated on a separate carrier and separately propagated.

40 Figure 3 is a diagrammatic representation of a single low frequency pulse as preferably modulated on a high frequency pulse train.

Figure 4 is a diagrammatic representation of a television receiver adapted to receive signals 45 either from the carrier of the system as shown in Figure 1, or simultaneously from two carriers, as shown in Figure 2.

Figure 5 is a circuit diagram of a thermionic tube adapted to demodulate and separate the 50 high and low frequency synchronizing pulses.

Figure 6 is a schematic diagram indicating the essential connections within certain of the equipment shown as blocks in the diagrams in Fig. 1.

In television systems, there are a large number 55 of different ways in which synchronizing pulses

or synchronizing energy in one form or another may be transmitted to the receiving station there to be utilized in maintaining the spatial relationship of the received picture. It is believed that wide reference to these many methods need not be made here. One of them, however, has been described and claimed in my Patent No. 1,773,981, wherein the low scanning frequency is modulated on the high scanning frequency and the modulated scanning frequency is again modulated on the carrier together with the signal, for transmission. The general details of this system are also disclosed in a prior patent, No. 1,773,980, of which the one just referred to is a division.

It should be noted, however, that in the above 15 cases the synchronizing frequencies are sine waves, and in that respect the present application differs, in that it broadly concerns the use of unidirectional synchronizing pulses upon which a lower frequency pulse is modulated, preferably 20 by reduction in amplitude of the higher frequency pulses during the lower frequency pulse period. The pulses are preferably derived from the energy used for the scansion used to create picture signals.

I have also found that it is preferable to transmit synchronizing pulses of this kind over a separate carrier, preferably identical with, or which differs from the carrier propagating the signal impulses by not more than plus or minus the 30 signal impulse frequency. It should, however, be understood that both pulses and signals can be propagated by a single carrier, and the reasons for my preference for two carriers will be apparent later in this description.

In the broad statement above, I have used the word "propagate" with respect to the carriers, as it should be understood that these carriers may be radiated into space or may be propagated in other ways well known in the art such as, for 40 example, carrier transmission on wires, or transmission lines, and I do not wish to be limited in the scope of my invention to the use of carriers radiated through space alone.

These and other broad aspects of my invention 45 may be more fully understood by reference to the drawings:

In Figure 1, I have shown a television image dissector 1, provided with a conventionalized lens 2 for focusing an image of an object 3 upon the 50 interior of the dissector. I prefer to utilize the cathode ray beam dissector disclosed in the patents above referred to, although any of the modifications thereof can be used, or cathode ray image dissectors of other kinds are equally satis- 55

factory. In the dissector referred to, there is a photoelectric cathode upon which an optical image is directed. The emitted electrons are maintained in substantially parallel paths and are accelerated toward an apertured anode. The entire electron beam is acted on by deflecting means to scan the cross section of the beam and thus allow electrons from successive elementary areas of the cathode to enter the aperture to produce a train of television signals, each corresponding in intensity to the intensity of illumination of the elementary area scanned to produce the signal. My invention is also applicable to other scanning systems as will be noted later.

16 The cathode ray beam in the dissector is acted upon by the field of two deflection coils 4 and 5 so positioned as to deflect the beam, when energized, in two directions, preferably at right angles. One of these coils is supplied with energy from a high frequency oscillator 6. The entire picture field is scanned, preferably line by line, by the high frequency oscillator, and then returned to repeat the cycle by the low frequency oscillator 7. I prefer that both of these oscillators 20 deliver their energy to the scanning coils in such a way that there is a saw tooth wave form in the scanning coils. Such oscillators are known in the art and their detailed construction is no part of the instant invention. Suitable examples, however, are shown in my prior patents, Nos. 2,051,372, issued August 18, 1936, and 2,059,683, issued November 3, 1936, and in the patent to Farnsworth and Lubcke, No. 2,059,219, issued November 3, 1936.

25 The net result of the two saw tooth scanning components is that the object is slowly scanned across a line to produce signals, and the return made at high speed to begin the next line. This means that signal amplitudes will be relatively 30 large during the scansion of the line itself but will be relatively small during the return of the beam due to the high return speed, with the reception of a lesser number of electrons.

35 Synchronizing pulses are desired between lines and between pictures. In manufacturing these pulses use is made of the fact that the derivative of the saw tooth wave form used for scanning has approximately the desired pulse wave form, as is disclosed in detail in my copending application, 40 Serial No. 449,984, filed May 5, 1930. As there pointed out, the back E. M. F. across any inductive circuit carrying current of saw tooth wave form, such as the deflecting coils themselves, comprises a wave of this pulse type, the pulses 45 occurring during the "fly-back time"; i. e., during the negative or steep slope of the saw tooth wave. The application cited further shows the use of this pulse completely to interrupt the signal during the fly-back time, and in the further 50 exposition of this invention it will be assumed that this is done. Voltages of rectangular pulse wave form exist in various points in the generating circuits, or it may be generated by the use of a small transformer 101, 102 in series with the 55 deflection coils 4 and 5 respectively, the transformer preferably having a negligibly small primary inductance in comparison with the impedance of the scanning coils, the secondary being effectively open-circuited; in other words, 60 feeding merely the grid of a vacuum tube.

65 The showing of Fig. 6 indicates schematically a typical connection for the purpose. The tubes 104 and 105 represent the output tubes of typical saw tooth generators, corresponding, for example, to the tube 27 of Patent No. 2,059,219. The 70

75 secondaries of transformers 102 and 101 are connected through the lines 9 and 10 respectively to the modulator 11.

I then prefer to modulate the high frequency pulse with the low frequency pulse by applying both pulses to a tube 103 operating at its point of negative cut off. I apply the high frequency pulse positively to the grid of the tube and then apply the low frequency pulse negatively, this being accomplished in the instant case by proper poling of the transformers 101 and 102. The polarity of the pulses may also be regulated by using an amplification stage to reverse the polarity of one set of pulses, as is well known in the art. The resultant output is as shown in Figure 3, where the high frequency pulses 12 have been reduced in amplitude during the entire low frequency pulse period, as indicated by the labeled arrows.

Figure 3 is somewhat conventional in that the tops of the high frequency pulses are usually not exactly square, as shown in the drawings, but may have a slight curvature. This curvature, however, does not in any way affect the operation of the system but merely affects the mean amplitude to a slight extent.

In the meantime, the output of the scanning oscillators is acting on the beam of the dissector tube to create a series of trains of signals into the signal amplifier. As has been pointed out above, the current is not completely interrupted between lines but falls to such a low amplitude during the return of the beam that the effect may be, for all intents and purposes, considered as a complete interruption in the signal train, particularly as the variations occurring at that time do not enter into the operation of the system, nor can they be construed as any part of the picture signal.

Referring again to Figures 1 and 6, the modulated high frequency pulses may then be passed through a circuit 14 into a pulse modulator 15 where the synchronizing pulses may be combined in any customary manner with the signals as, for example, by connecting the output circuit 14 across the input resistor of an amplifier tube 105 45 in parallel with the output of the signal amplifier, and then the combined signal and pulses passed into a signal impulse modulator 16 where they are all modulated in the usual manner on a carrier, thence to be radiated through an antenna system 17. As the signals and pulses are out of phase, the pulses will take place during the interruptions in the signal current.

As it is preferable, however, to make the amplitude of the pulse frequencies in relation to the picture frequencies as large as possible, preferably not less than three or four to one, and more preferably five to ten to one, it can readily be seen that the output of the transmitter must be sufficiently large to handle the energy of the 60 pulses without in any way disturbing the efficient and undistorted radiation of the signal impulses occurring between the synchronizing pulses. This means that the transmitter must be much larger than would be necessary for the picture 65 frequencies alone. It should be noted that the synchronizing pulses are enormously larger than the minute variations occurring in the signal interruptions, and these variations, although superimposed on the pulses, are too small to be 70 noticed and later are eliminated, as will be described.

I prefer to split the work between two transmitters, as shown in Figure 2. Here the high frequency pulses, modulated by the low frequency 75

5 pulses, pass through a circuit 18 into a special transmitter 20 where the synchronizing pulses alone are modulated in the usual way onto a carrier for transmission by a synchronizing antenna system 21. In-as-much-as in this transmitter we are not concerned with the periods between the synchronizing pulses, and as the synchronizing pulses are of a transient nature, this transmitter may be highly overloaded as far as 10 the pulse amplitudes are concerned without employing a tube of excessively high power and without excessive heating. As this tube is preferably modulated to saturation, the small variations above referred to totally disappear at this point.

15 The output of the dissector tube is then passed directly through the signal amplifier into a signal modulator to modulate a separate carrier which may be radiated by the signal antenna system 22. The two carriers, one for the pulses and the other 20 for the signals, are simultaneously radiated, with the pulses 180° out of phase with the signal groups, i. e., the pulses are so phased in the modulator as to cause increasing amplitude of radiation with increasing pulse, while the picture modulation amplitude decreases with increasing light. 25 In other words, the pulses correspond to black, or "blacker than black" signals. I prefer that the carriers be of identical frequency; and it is quite convenient, in order to maintain these carriers at the same frequency, that both carriers be controlled, for example, by crystal control using a crystal common to both circuits. Other means, however, will suggest themselves to those skilled in the art.

30 35 It is obvious, however, that the carriers need not be at identical frequencies, all that is necessary for reception of both carriers by a single receiver being that the two carriers be within the side bands covered by the signal frequencies; 40 that is, that they shall not differ by more than plus or minus the signal frequency.

The above, however, will only hold when it is desired that the two carriers be received by a single receiving set. It is quite within the bounds 45 of my invention that the signals and pulses be received separately, and combined after the elimination of the carriers.

It will be noted, therefore, that in my preferred system, using either a single carrier or two separate carriers at identical or closely adjacent frequencies, that a composite television signal will be received by a single receiver, this signal comprising groups of television signals having therebetween large amplitude synchronizing impulses, 50 these synchronizing impulses being reduced in amplitude at regular intervals corresponding to the low scanning frequency.

A preferred receiving circuit is shown in extreme lowest terms in Figure 4. Here the entire 55 train of signals together with the pulses, is received by a signal and pulse receiver 24, rectified and passed to the grid of the cathode ray tube 25. This grid will, therefore, have impressed upon it signal frequencies and pulse frequencies. I prefer to apply the composite current to the grid with the pulse frequencies applied negatively. This may be accomplished by regulating the number of amplification stages in the receiver.

The cathode ray tube 25 has also associated 60 with it, receiving scanning coils 26 and 27 energized by a receiving high frequency oscillator 28 and a receiving low frequency oscillator 29, these oscillators also being preferably so regulated as to cause a saw tooth wave form in the scanning 65 coils similar to that used in the transmitter.

I prefer to utilize a portion of the saw tooth output of these oscillators to throw the grid of the cathode ray tube highly negative during the return of the beam to start the line of scanning, as described in the application of Farnsworth, Serial No. 449,984, filed May 5, 1930, for a "Television scanning and synchronizing system". There a portion of the output of the scanning generator passes through a transformer, and the sharp field collapse, due to the descending portion of the wave, creates an intense negative pulse which is applied to the cathode ray grid, extinguishing or greatly reducing the brilliancy of the spot. Thus what occurs in the remainder of the circuit during this period makes no direct impression on the received picture, and as the synchronizing pulses are also negative, the effect is merely enhanced. In fact, it is quite possible to utilize the negative high frequency synchronizing pulse on the grid to extinguish or dim the spot 10 between lines without recourse to a special pulse for that purpose. This effect, however, is no part of my present invention, and will be elsewhere described and claimed.

15 The composite current comprising pulse and signal is also passed into a pulse demodulator 31.

20 As I desire to apply the high frequency pulses to this demodulator positively, I may either take off the synchronizing pulses from the receiver amplifier at some stage ahead of the television signals where the phase will be correct, or I may add another stage to reverse the phase of the pulses. I have found it convenient to so arrange my receiver circuits that I take the pulses off 25 positively after the receiver detector, and continue the amplification of the signals through the proper number of stages so they will be applied to the grid negatively. I have sometimes found it convenient to adjust my amplification stages to 30 reduce the pulse energy in the circuits leading 35 positively yafter the receiver detector, and connect to the cathode ray tube after having taken off the pulses from the detector.

I then provide an over biased tube 32, the tube being preferably self biased by the introduction 40 of a leak resistor 33 and condenser 34 in a cathode lead. I also prefer to place a grid resistor 35 from grid to ground. Proper regulation of values in the resistor 33 and condenser 34 will provide a strong bias which will persist during the 45 low frequency pulse period. As these values will be different with different scanning frequencies no values will be given, but such regulation is well known to those skilled in the art.

The anode 36 is in series with a high frequency 50 resistor 37 and a low frequency resistor 38, and of course the usual anode supply. The low frequency resistor 38 is also shunted by an integrating condenser 39. A high frequency pulse lead 40 is taken directly off the anode through a high 55 frequency blocking condenser 41 and a low frequency pulse lead 42 taken off between the two resistors 37 and 38 through a similar low frequency blocking condenser 44. The leads 40 and 42 go directly to the synchronizing grids of the 60 respective high and low frequency scanning oscillators. Here again, the relative values of resistance and capacity will vary in accordance 65 with frequency.

70 As the high frequency pulses are applied positively to the grid, they will appear negatively in the pulse lead 40. The low frequency interruption of these pulses will cause a decrease in the current and they will therefore appear as positive pulses in the low frequency lead 42. These 75

polarities are exactly those desired for application to the respective synchronizing grids of the scanning oscillators.

When applied to these grids the pulses serve to hold the receiving scanning oscillators in step with the scanning oscillators at the transmitter, from which the pulses were derived.

Thus it will be seen that the picture formed by the cathode ray beam impinging on the fluorescent screen of the receiving tube will be held in step with the picture scanned at the transmitter, the synchronizing pulses having been transmitted between the signal groups representing the lines of the picture.

15 It will be obvious that my invention may be applied to systems other than those using cathode ray dissector tubes. In case a Nipkow disc or similar scanning means is used synchronizing pulses may be generated by the use of synchronizing apertures in the disc located between lines, and the energy thus produced may be handled as a series of unidirectional pulses modulated by a low frequency pulse between pictures. After generation, the synchronizing pulses may 20 be handled as above described in carrying out my invention as applied to a dissector tube.

It should also be noted that electrostatic deflection of the dissector beam may be used, a derivative of the deflection energy being used for 30 the synchronizing pulses, such adaptation being obvious. Furthermore, while my preferred dissector comprises the use of a broad cathode ray beam scanned past an aperture, my invention is equally applicable to those cathode ray dissectors 35 wherein a photo-sensitive mosaic is scanned, directly or indirectly by a narrow cathode ray beam to produce a train of television signals. In fact the invention is applicable to any of the known scansion devices used to produce a train of television signals.

40 The advantages of my invention are numerous. The use of unidirectional pulses allows amplitude reduction modulation to provide low frequency pulse periods. The unidirectional pulses being 45 transient in nature allow the use of tubes modulated to saturation without excessive heating. The pulses, being unidirectional are available for application to vacuum tubes either positively or negatively as desired, for either action thereon 50 or for other purposes, brilliancy reduction for example, as in the receiving tube. The pulses may be passed, or stopped, as desired, by the use of an over-biased tube, or separated as in the case 55 of the demodulator at the receiving end. By reduction modulation of the pulses as described, synchronizing pulses may be obtained, of opposite polarity, this opposition being valuable in the use of the pulses at the receiving end, for synchronization.

60 Furthermore, the use of separate carriers, one for the picture signals and one for the synchronizing pulses, greatly reduces the total amount of power necessary at the transmitter, does in fact reduce the complexity of the transmitter as a whole, and reduces interference between signals and synchronizing pulses at the transmitter, thus reducing picture distortion.

I claim:

1. In television, the method of synchronizing 70 which comprises the steps of generating a train of relatively high frequency unidirectional pulses, interrupting said train at regular relatively low frequency intervals, and modulating a carrier with the interrupted train for transmission as a 75 synchronizing component.

2. In television, the method of synchronizing which comprises the steps of generating a train of relatively high frequency unidirectional pulses, reducing the pulse amplitude of said train at regular relatively low frequency intervals, and modulating a carrier with the interrupted train for transmission as a synchronizing component. 5

3. In television, the method of synchronizing which comprises the steps of scanning an object to produce an interrupted series of signal impulses generating a train of relatively high frequency unidirectional pulses, interrupting said train at regular low frequency intervals, modulating a carrier with said signal impulses, modulating the same carrier with said interrupted 15 train, and interlocking said train and said series with said pulses positioned in the interruptions of said signal train.

4. In television, the method of synchronizing which comprises the steps of scanning an object 20 to produce an interrupted series of signal impulses generating a train of relatively high frequency unidirectional pulses, interrupting said train at regular low frequency intervals, modulating a carrier with said signal impulses, modulating a second carrier of identical frequency with said interrupted train, simultaneously radiating both carriers, and interlocking said train and said series to radiate said pulses in the interruption of said signal train. 25

5. In television, the method of synchronizing which comprises the steps of scanning an object to produce an interrupted series of signal impulses, generating a train of synchronizing pulses at the frequency of signal interruption, 30 generating a carrier and modulating both said signals and said synchronizing pulses on said carrier, said pulse modulation being of opposite sign to the modulation produced by light in said signal impulses. 35

6. In television, the method of synchronizing which comprises the steps of scanning an object to produce an interrupted series of signal impulses, generating a train of synchronizing pulses at the frequency of signal interruption, 45 modulating separate carriers of identical frequency with said signal series and said synchronizing pulses respectively, and simultaneously radiating said modulated carriers, said pulse modulation being of opposite sign to the modulation produced by light in said signal impulses. 50

7. In television, the method of synchronizing which comprises the steps of generating a series of unidirectional synchronizing pulses, and reducing the amplitude of a group of said pulses 55 at regular intervals.

8. In television, the method of synchronizing which comprises the steps of generating a scanning current, scanning an object therewith to produce an interrupted series of signal impulses, deriving a train of unidirectional synchronizing pulses from said scanning current, said pulses being of the order of from three to ten times the amplitude of said signal impulses, modulating a carrier with said signal impulses, 60 modulating a second carrier having a frequency equal to said first carrier plus or minus the frequency of said signal impulses with said synchronizing pulses, and simultaneously propagating said carriers. 65

9. In television, the method of synchronizing which comprises the steps of generating a scanning current, scanning an object therewith to produce an interrupted series of signal impulses, deriving a train of unidirectional synchronizing 70 pulses, and simultaneously propagating said carriers. 75

5 pulses from said scanning current of opposite sign to the signals produced by illumination of said object, said pulses being of the order of from three to ten times the amplitude of said signal impulses, modulating a carrier with said signal impulses, modulating a second carrier having a frequency equal to said first carrier plus or minus the frequency of said signal impulses with said synchronizing pulses, and simultaneously 10 propagating said carriers.

10. In television, the method of modulating a high frequency train of unidirectional synchronizing pulses with a low frequency pulse which comprises biasing the control electrode of a three electrode tube to cut-off, applying the high frequency pulses to said grid positively, and applying said low frequency pulse to said grid negatively thereby reducing the amplitude of the resultant output pulses during the period of said 15 low frequency pulses.

15. In television, a cathode ray image dissector, a high frequency scanning oscillator, a low frequency scanning oscillator, means for deflecting said beam with energy generated by said oscillators, a thermionic tube having a grid biased to cut-off, means for applying energy from said high frequency oscillator to said grid positively, and means for applying energy from 20 said low frequency oscillator to said grid negatively, the output of said tube being used as a 25

30

synchronizing component in a television system.

12. In television, a cathode ray image dissector, a high frequency scanning oscillator, a low frequency scanning oscillator, means for deflecting said beam with energy generated by 5 said oscillators, a thermionic tube having a grid biased to cut-off, means for applying energy from said high frequency oscillator to said grid positively, and means for applying energy from 10 said low frequency oscillator to said grid negatively, the output of said tube being transmitted as a synchronizing component, and the output of said dissector being transmitted as a signal component.

13. In television, a cathode ray image dissector, a high frequency scanning oscillator, a low frequency scanning oscillator, means for deflecting said beam with the energy generated by said oscillators, a thermionic tube having a 15 grid biased to cut-off, a means for applying energy from said high frequency oscillator to said grid positively, means for applying energy from said low frequency oscillator to said grid negatively, means for modulating the output of said 20 tube on a carrier, and means for modulating the output of said dissector on a second carrier, said carriers being simultaneously radiated.

PHILO T. FARNSWORTH. 30
